SUCTION CLEANER

Charles H. Taylor, North Canton, Ohio, assignor
to The Hoover Company, North Canton, Ohio,
a corporation of Ohio

Application December 23, 1935, Serial No. 55,794

8 Claims. (Cl. 15—5)

The present invention relates to suction cleaners in general and particularly to improvements in the agitating means of suction cleaners. More specifically, the invention comprises a new and improved rotary agitator in which the beating element rotates upon its own axis at a speed controlled by the speed of rotation of the agitator.

It is an object of the invention to provide a new and improved suction cleaner. It is another object of the invention to provide a new and improved suction cleaner agitator. A still further object of the invention is to provide a new and improved rotary agitator for a suction cleaner. Still another object of the invention is to provide a rotary agitator in a suction cleaner in which the horizontal component of movement of the beater element relative to the surface covering at the point of surface contact is eliminated. A still further object is the provision of a rotary agitator for a suction cleaner in which the frictional contact of the agitator with the surface covering is reduced. These and other more specific objects will appear upon reading the following specification and claims and upon considering in connection therewith the attached drawings to which they relate.

Referring now to the drawings, in which preferred embodiments of the present invention are disclosed:

Figure 1 is a front view of a suction cleaner embodying the present invention, with a part of the cleaner casing broken away to show an agitator constructed in accordance with the present invention embodied therein;

Figure 2 is a partial longitudinal section through the agitator constructed in accordance with the present invention;

Figure 3 is a section through the agitator shown in Figure 2 looking in the direction of the arrows upon the line 3—3;

Figure 4 is a section similar to Figure 3 but looking in the direction of the arrows upon the line 4—4;

Figure 5 is a section upon the line 5—5 of Figure 2;

Figure 6 is a longitudinal section through the second embodiment of the present invention;

Figure 7 is a partial longitudinal section through an agitator constructed in accordance with a third embodiment of the invention;

Figure 8 is a section upon the line 8—8 of Figure 7.

Modern suction cleaners embody surface agi-

tating means which cooperate with the air flow through the cleaner to remove the embedded foreign material from the surface covering undergoing cleaning. The most effective agitating means today comprise rotary agitators provided with beating elements. These agitators rotate relative to the surface covering which is lifted thereagainst by the suction of the cleaner. The rotation of the elements functions to beat and vibrate the surface covering, causing embedded foreign material to be displaced therefrom. The rotation of the cleaner results in a sliding friction between the beating elements and the surface covering at the point of contact. In the agitator constructed in accordance with the present invention, the beater element rotates relative to the body of the agitator in which it is mounted so that the sliding movement between the element and the surface covering undergoing cleaning is materially reduced or eliminated. This improvement is advantageous in that frictional wear of the surface covering is eliminated and the load upon the cleaner motor is correspondingly reduced.

Referring again to the drawings, and to Figures 1 to 5 inclusive in particular, a rotary agitator constructed in accordance with the present invention is shown embodied in a modern suction cleaner. The suction cleaner comprises a nozzle 1 which is interiorly connected to a fan chamber 2 within which is positioned a rotating suction-creating fan 3. Above the fan chamber 2 is positioned a motor casing 4 which houses an unshown driving motor for the fan 3, the shaft 5 of which extends downwardly from the casing 4, through the fan chamber 2, and into the passageway connecting with the nozzle 1. The cleaner is suitably supported upon front and rear wheels 6, 6 and 6a, 6a, respectively. A handle 7 is pivoted to the machine and makes it possible for the operator to propel the cleaner over the surface covering undergoing cleaning. Within the nozzle 1 is positioned an agitator indicated generally by the reference character 8. Agitator 8 is suitably driven by the motor shaft 5 by the power-transmitting belt 9 in a common and well known manner.

The parts hereinbefore described are common in suction cleaners and in operation function as follows:

The unshown driving motor causes suction-creating fan 3 to rotate and to create a suction which is effective within the nozzle 1. This reduced pressure causes the surface covering po-

sitioned below the nozzle to be lifted into contact with the nozzle lips which are indicated by the reference characters 1A and 1B. Inrushing air into the nozzle between the lips and the surface covering functions to remove much of the embedded foreign matter in the surface covering. The rotating agitator 8 within the nozzle, driven by the belt 9 from the motor shaft 6, contacts the lifted surface covering between the nozzle lips, and, through being provided with rigid beating elements and brush elements, functions to vibrate and brush the surface covering, and to dislodge therefrom embedded foreign matter which is removed by the inrushing air into the nozzle and carried to the fan chamber from which it passes into an unshown dust bag in a common and well known manner. The present invention comprises the improved construction of the agitator 8 which is so designed that it performs its cleaning function with maximum efficiency and minimum covering wear.

Referring now to Figures 2 to 5 inclusive in particular, the specific structure of the first embodiment of the agitator is shown. The body of agitator 8 is an elongated cylindrical member which is formed centrally with a circumferential pulley surface 10. The cylindrical body of agitator 8 is rotatively supported at its ends upon a longitudinally extending stationary shaft 11 by means of bearings 12 which are seated in the removable end walls 13 of the body. The opposite ends of the agitator are identical, and one end is illustrated in Figure 2. The extremities of the shaft 11 are threaded and a nut 14 secures the bearing in place in its seat in the end wall 13. A thread guard 15 is carried by nut 14 and overhangs the end of cylindrical body 8 to prevent the accumulation of foreign matter in and around the bearing. The body of the agitator 8 upon each side of the centrally located pulley surface 10 is provided with a rigid cylindrical beater element 16 and a flexible brush element 17. These elements are circumferentially spaced around the body 8 and extend partially within the normal contour of the body in seats 18, 18.

Beater element 16 is a rigid cylindrical member which is mounted upon the rotatable longitudinally extending shaft 18 which is seated at its ends within bearings 20 and 21, the former being positioned in the center or pulley end of the seat while the latter is carried by the removable end wall 13. Beater element 16 is geared to the stationary, non-rotating shaft 11 by means of a gear train comprising a gear 22 carried by its own shaft 19, a large diameter stationary gear 23 mounted upon shaft 11, and an intermediate gear 24 carried by the end wall 13 which transmits power between the first two mentioned gears. As agitating element 16 is carried by the agitator body around the shaft 11 as a center, in the rotation of the agitator, it is clear, as is readily seen in Figure 3, that as gear 24 rolls around stationary gear 23, it will impart to gear 22 a rotation which will cause its exposed surface, above the normal surface of agitator 8, to move directly opposite to the direction of movement of the agitator surface. At the outermost point of element 16, that element is stationary at any given instant, the speed of rotation of element 16 about its own center cancelling the speed of rotation of the agitator 8 about the common center 11. By a correct choice of ratios in the gears 22, 23 and 24, the relative speed of element 16 can be controlled and that element at its outer-

most point can have a slight forward movement with the agitator 8, can stand still relative to the surrounding and adjacent surface covering being contacted, or can have a positive movement opposed to the direction of movement of agitator 8 surface.

The brush 17, which is spaced circumferentially from the beater element 16, comprises a centrally bored body 25 within which is mounted a spirally extending row of flexible brush elements which surround the body. As in the case of beater element 16, brush 17 is rotatably mounted upon a supporting shaft 19 carried by bearings 20 and 21 and the brush is geared to the stationary shaft 11 in the manner of the beater element 16. It is not necessary that the speed of rotation of brush 17 about its own center be identical with the speed of rotation of beater element 16. As in the case of the beater element the speed and direction of movement of the brush 20 at its surface contacting portion can be controlled by the proper selection of gears.

In the case of both the rotating beater element and the rotating brush element, the surface covering undergoing cleaning is lifted into contact therewith and is depressed thereby. The individual rotation of these elements relative to the agitator body in no way decreases their effectiveness as means to displace vertically the surface covering undergoing cleaning for the purpose of dislodging therefrom the embedded foreign material. In a preferred form the result of the individual and separate rotation of these elements is that they no longer move or slide across the surface covering with the speed of agitator rotation. This frictional movement is dependent upon the relative speed of the element relative to the agitator and may be entirely eliminated or may be merely reduced, depending upon the ratio of the gears connecting the elements to the stationary shaft.

Referring now to Figure 6 in particular, a modified embodiment of the present invention is illustrated in which the rotating brush elements have been eliminated from the agitator and the rigid beater elements 16 are relied upon wholly to perform the agitating function. In this embodiment as in the former, the agitator 16 is power driven and rotates upon its own shaft 18 through the action of connecting gears as illustrated in Figure 3.

Referring now to Figures 7 and 8, the third preferred embodiment of the invention is illustrated. In this embodiment the surface-contacting elements are again rotated about their own axes, but the gears 22, 23 and 24 have been replaced by a friction drive in which a grooved wheel 28 is mounted upon the element shaft 19 and a large diameter grooved wheel 29 is mounted upon and carried by stationary agitator shaft 11. An intermediate wheel 30 is formed with a rim adapted to seat within the grooves of wheels 28 and 29 and is itself mounted upon a lever 31 pivoted upon the agitator end plate 13 and spring pressed into contact with wheel 29 by a torsion spring 32 at the pivot point of the lever. The operation of this embodiment of the invention is exactly like the previous embodiments.

I claim:

1. In a rotary surface covering agitator for a suction cleaner, a rotatable cylindrical agitator body adapted to be rotated about an axis parallel to a surface covering undergoing cleaning, means to support said body for rotation about its major axis and parallel to the plane of a surface cover-

- ing undergoing cleaning, a surface-agitating element extended radially beyond said body at the side thereof adapted to contact a surface covering undergoing cleaning positioned below said body in certain angular positions of said body, and means mounting said element for rotation with said body about the axis of rotation thereof and also for rotation about an axis radially spaced from said first-mentioned axis, and means 10 to rotate said element upon the rotation of said body and in the opposite direction to give to the outermost surface-contacting portion thereof a peripheral speed relative to the axis of said body different than the peripheral speed of a point fixed relative to said body and moving at the same rotational speed as said body.
2. In a rotary agitator for a suction cleaner, a body, means to mount said body rotatably, a seat in the surface of said body, a surface-agitating element in said seat and extended therefrom, means mounting said element for rotation about an axis parallel to the axis of rotation of said body, a stationary friction wheel connected to the means to mount said body, a wheel connected to said element, and a third wheel connected to said rotatable body spring-pressed into contact with said two first-mentioned wheels, said wheels causing said element to rotate upon its own axis upon the rotation of said body.
3. In a suction cleaner rotary agitator, a rotatable body, a surface-agitating element extended radially beyond the adjacent portions of said body, means mounting said element for movement of the surface-contacting portion thereof relative to said body, and means to move said element to impart to the surface-contacting portion thereof a speed equal and opposite to its circumferential speed resulting from the rotation of said body.
4. An agitator for a suction cleaner comprising a rotatable body, a stationary support therefor to support said body for rotation about a horizontal axis, a surface agitating element rotatably mounted in said body and adapted to make surface contact in certain angular positions of said body at the side thereof, and means cooperating with said body, support and element to cause positively a relative rotational movement between said element and said body when said body is rotated to reduce the surface-contacting speed of said element.
5. In an agitator for a suction cleaner, a body, a support on which said body is adapted to be mounted for rotation about an axis parallel to the plane of a surface covering undergoing cleaning, an agitating element seat in the surface of said body, a surface agitating element rotatably mounted in said seat and projecting therefrom, the axes of rotation of the body and element being parallel, a gear train cooperating with the body, the support therefor and the surface contacting element to cause rotation of the said element when said body is rotated to reduce the surface-contacting speed of said element.
6. In a rotary surface-contacting agitator for suction cleaners, a cylindrical body formed with an elongated recessed seat in its cylindrical surface, an elongated surface-agitating element partially positioned in said seat and extended radially beyond said body, said element being mounted for rotation about an axis parallel to the major axis of said body, means to mount said body for rotation about said major axis, means mounting said element for rotation in said seat about an axis parallel to the major axis of said body with a minimum frictional resistance, a stationary gear positioned within said body, and a gear rotatable with said element and operatively connected to said stationary gear to impart rotation to said element upon rotation of said body to reduce the surface-contacting speed to the outermost portions of said element.
7. A rotary surface covering agitator comprising a body rotatable about a longitudinal axis, a rigid surface-agitating element extended radially beyond said body, means mounting said element for rotation relative to said body about an axis parallel to and radially spaced from the axis of rotation of said body, and means to rotate said rigid surface-contacting element relative to said body and in the opposite direction to reduce the peripheral speed of said element about the axis of agitator rotation.
8. A rotary surface covering agitator comprising a body rotatable about a longitudinal axis, a cylindrical flexible surface-agitating element extended radially beyond said body relative to said axis, means mounting said element for rotation relative to said body about an axis parallel to and radially spaced from the axis of rotation of said body, and means to rotate said element relative to said body and in the opposite direction to reduce the peripheral speed of said element about the axis of agitator rotation.

CHARLES H. TAYLOR.
